CONVERTIBLE DRESS

Paula M. Ackley, Vineland, N. J.

Application April 5, 1947, Serial No. 739,572

1 Claim. (Cl. 2—74)

1

This invention relates generally to women's wearing apparel and more particularly to an improved construction of a convertible dress having a readily removable front panel which is interchangeable with another panel to completely change the appearance of the dress as desired.

Among the principal objects of the present invention is to provide a novel arrangement of a convertible dress which comprises, in combination, a basic unit forming the back, shoulders and sleeves of the garment and a front panel quick-detachably secured to the basic unit to complete the dress, the front panel being interchangeable with another of such different design as to convert the general appearance and style of the dress.

Other objects and advantages of the present invention will appear more fully hereinafter, it being understood that the present invention consists generally in the combination, construction, location and arrangement of the several parts as hereinafter described in detail, as shown in the accompanying drawings and as finally pointed out in the appended claim.

In the drawings, which are illustrative of a garment constructed in accordance with and embodying the principles of the present invention:

Figure 1 is a front elevational view of a dress, the appearance of which is characterized by the use of a detachable front panel of a particular design;

Figure 2 is a front elevational view similar to Figure 1 showing the appearance of the dress converted by the use of a different design of detachable front panel;

Figure 3 is a rear elevational view of the detachable front panel employed to produce the dress of Figure 1;

Figure 4 is a front elevational view of the back of the dress which constitutes the basic unit thereof;

Figure 5 is a sectional view taken on the line 5—5 of Figure 4;

Figure 6 is a sectional view taken on the line 6—6 of Figure 1; and

Figure 7 is a sectional view taken on the line 7—7 of Figure 3.

Referring now more particularly to the drawings, it will be observed that the garment of the present invention consists of a women's dress having a basic back part 10 and an interchangeable front panel part 11. As most clearly appears in Figure 4, the basic back part 10 of the dress comprises in addition to the full body portion of the back of the dress the shoulder por-

tions 12—12 and the marginal side portions 13—13 which extend vertically the full length of the dress from the bottom edge of the skirt portion 14 to the shoulder portions 12—12 of the dress. The shoulder portions 12—12 of the basic unit 10 include the sleeve parts 15—15 which may be of the short type shown in the drawings or of greater length as may be desired, it being understood, of course, that said basic unit 10 is fashioned in conventional manner to properly conform the shape of the garment to the body of the wearer.

Secured to and extending along each of the opposite marginal edges of the basic back part 10 of the garment is a course 16 of slide-fastener elements, each course of said elements being so secured in position upon the external face of the part 10 by a line of stitching 17 as to locate each course of the slide-fastener elements substantially in coincidence with each free fashioned edge 18 of the part 10 of the garment. As most clearly appears in Figure 4, the courses 16—16 of the slide-fastener elements extend substantially the full length of the garment part 10, that is, from the bottom edge of its skirt portion 14 upwardly to the neck line 19 of the garments.

As appears most clearly in Figure 3, the front panel part 11 of the convertible dress is of a shape and form adapted to be joined to the basic back part 10 to complete the dress, it being observed that the opposite side edges 20—20 of this front panel part are shaped in general correspondence with the shape of the fashioned edges 18—18 of the basic back part 10. Secured to and extending along each marginal edge of the front panel 11 is a course 21 of slide-fastener elements, each course thereof being secured in position upon the inner face of the panel by a line of stitching 22. Preferably, the courses 21—21 of the slide-fastener elements are spaced somewhat inwardly of the marginal side edges of the panel so as to provide marginal flap portions 23—23 which respectively overlie the vertically extending marginal portions of the back part 10 when the two parts 10 and 11 are assembled as shown in Figures 1 and 6, these flap portions 23—23 thus serving to conceal from view the interengaged courses of the slide-fastener elements. It will be understood, of course, that to assemble the two parts 10 and 11 to form the complete dress, it is merely necessary to engage the slide-fastener elements extending along opposite sides of the front panel 11 with those extending along the corresponding sides of the back part 10.

Figure 2 illustrates the use of a front panel 11a

different from that employed to make up the dress of Figure 1, this front panel 11^a being of the same general construction as that of the panel 11 so that it is interchangeable with the latter. By forming the two panels of different materials or patterns, or by changing the neck lines thereof, as illustrated, dresses of entirely different appearance may be obtained simply by assembling with the basic back part 10 one or another of several interchangeable front panels. Thus, by providing two or more front panels of different design and appearance for interchangeable assembly with a single basic back part, an entirely different appearance and style of dress may be obtained as desired, thus obviating the necessity of carrying along two or more complete dresses for such occasions as may require a change in attire.

It will be understood, of course, that the present invention is susceptible of various changes and modifications in the construction and arrangement of its several parts, all without departing from the general principles or real spirit of the present invention and it is accordingly intended to claim the same broadly, as well as specifically, as indicated by the appended claim.

What is claimed as new and useful is:

In a convertible dress of the character described, a basic part having shoulder and waist portions form-fashioned to conform to and fit over the back and shoulders and about the waist of the wearer's body, said basic part including a skirt portion depending from the waist portion thereof, the shoulder, waist and skirt portions of said basic part of the dress having opposed marginal edges which extend continuously the full length of the dress from the bottom edge of its skirt portion to the upper edge of its shoulder portion, said edges being so relatively disposed along the opposite frontal sides of the wearer's body, when the dress is worn, as to provide an

open space transversely between said edges across the front of the wearer's body, said edges being respectively provided with continuous courses of slide-fastener elements, and a front panel fashioned to fit over the front of the wearer's body and cover said open space between the marginal edges of said basic part, said panel including waist and skirt portions complementary to the shoulder, waist and skirt portions of said basic part to complete the dress upon securing of said front panel to said basic part, said front panel being provided along its opposite marginal edges with continuous courses of slide-fastening elements respectively engageable with those of the basic part, the fastening elements on said front panel being spaced inwardly of its marginal edges to provide said panel with marginal flaps which cover and conceal from view the interengaged fastening elements, said front panel being generally of hour-glass shape in perimetral outline and being interchangeable with another front panel of corresponding shape and size but of different appearance and style to convert the appearance of the dress accordingly as the front panel thereof is changed.
